JOHN F. DODGE AND WILLIAM J. ALLES, OF DETROIT, MICHIGAN, ASSIGNEES TO DODGE BROTHERS, OF DETROIT, MICHIGAN, A CORPORATION OF MICHIGAN.

METHOD OF MANUFACTURING PISTON-RINGS.

1,255,142.

Specification of Letters Patent. Patented Feb. 5, 1918.

Application filed May 12, 1917. Serial No. 168,111.

To all whom it may concern:

Be it known that we, JOHN F. DODGE and WILLIAM J. ALLES, citizens of the United States, residing at Detroit, Mich., have invented certain new and useful Improvements in Methods of Manufacturing Piston-Rings, of which the following is a clear, full and exact description.

This invention relates to an improved 10 method of manufacturing piston rings for internal combustion engines or those of other types.

One of the objects of this invention is to provide a method by which the stiffness of 15 a piston ring may be increased and made to vary continuously around the circumference of the ring so that when the ring is contracted in a cylinder, a practically uniform outward pressure will be exerted at all 20 points of contact between the ring and cylinder.

Another object of this invention is the provision of a method for easily and cheaply increasing the density and stiffness of the 25 material in a piston ring.

The method of manufacture hereinafter 30 to be described, consists broadly in compressing the entire inner surface of the ring in continuously varying degrees around the circumference so that the stiffness of the ring against bending in a plane normal to its axis varies continuously from point to point. This stiffening effect is a maximum 35 at the point diametrically opposite the gap and gradually decreases around the circumference from this point to the gap, where it becomes zero.

One method of producing the above described effect is as follows: a cylindrical 40 casting, having its internal and external diameters respectively less than and larger than the corresponding diameters of the finished ring, is bored out to a diameter slightly greater than the internal diameter 45 of the finished ring and the exterior of the casting is turned to a diameter slightly larger than the bore of the cylinder which it is to fit. The internal surface of the casting is then compressed by rolling it with a 50 hardened roller or rollers so that the metal is made very hard and dense at the surface, this effect extending to an appreciable distance into the interior of the metal. The casting is then bored out eccentrically, so

that the part of the metal which has been 55 affected by the rolling is entirely removed at one point in the circumference, while the surface at the point diametrically opposite is not touched. This has the effect of varying the stiffness of the casting at various 60 points around the circumference. The casting is then divided on planes perpendicular to its axis, thus forming solid rings which are then ground on their flat faces to produce true surfaces at the proper distance 65 apart. The rings are then sawed through at the point where the material affected by the rolling has been entirely removed and the proper amount of material taken off the 70 ends so that when the ends are brought together, the rings will have the desired diameter. The rings are then placed in a chuck which holds the ends together while the outer cylindrical surface is ground to the exact diameter required.

A second and alternative method which produces the same effect in a slightly different way is carried out as follows: The cylindrical casting is first machined to the proper dimensions as described above, but, instead of being rolled uniformly all over its interior surface, it is acted upon by a roller or series of rollers revolving about an axis eccentric to the axis of the casting so that the pressure exerted upon the casting by the rollers varies at different points in the circumference. With this process, the eccentric boring operation is unnecessary, but the other operations to complete the ring remain as above described, these operations consisting in dividing the casting on planes perpendicular to its axis, thus forming solid rings in the manner hereinabove described in connection with the first method, which are then ground on their flat faces to produce true 85 surfaces at the proper distance apart; then sawing through each of these rings at the point where the application of the pressure has been least or, in other words, at the point where the tension produced upon the inner 90 surface of the ring is least. This point will obviously coincide with the point of least reduction in thickness by the rolling operation.

Owing to the fact that the omission of the eccentric boring operation makes this second method somewhat cheaper than the one first described, it is of greater commercial importance and this application will be de-

voted largely to a description of the means and methods used in applying it to practice, though the same apparatus, with slight changes in the adjustment, can also be used 5 in carrying out the first method.

Instead of rolling the interior of the casting which is later divided into a number of piston rings, the rolling process above described may, of course, be applied to the individual rings if desired.

Referring to the drawings:

Figure 1 is an elevation showing an arrangement suitable for rolling the internal surface of a piston ring casting in a lathe.

15 Fig. 2 is a vertical section on the line 2-2 of Fig. 1.

Fig. 3 is a plan view of the holder in which the piston ring casting is held.

20 Fig. 4 is an end view thereof.

Fig. 5 shown partly in section, is a detail 25 of the means used for holding and adjusting the roller.

Fig. 6 is a section taken on line 6-6 of Fig. 5.

25 Fig. 7 is a bottom plan view of the apparatus shown in Fig. 5.

Fig. 8 is a top plan view thereof.

Fig. 9 is an elevation showing a second 30 arrangement for rolling the interior of a piston ring casting in a lathe.

Fig. 10 is a vertical section on the line 10-10 of Fig. 9.

Fig. 11 is a plan view of the work holder 35 shown in Fig. 9.

Fig. 12 is an end elevation thereof.

Fig. 13 is an elevation showing a third 40 arrangement for rolling the interior of a piston ring casting in a lathe.

Fig. 14 is a vertical section on the line 45 14-14 of Fig. 13.

Fig. 15 is a plan view of the work holder shown in Fig. 13.

Fig. 16 is an elevation thereof.

Fig. 17 is an elevation showing an arrangement for rolling the interior of a piston ring casting on a drill press.

Fig. 18 is a horizontal section on the line 45 18-18 of Fig. 17.

Fig. 19 is an elevation of the work holder 50 shown in Fig. 17.

Fig. 20 is a plan view thereof.

In Fig. 1 the piston ring casting 10 is shown 55 clamped in the holder 11 which is supported on the tool carriage 34 of a lathe. The work holder is provided with an upper clamping portion 12 which is hinged to the lower part and held down against the piston ring casting by the bolts 13, the holder being bored out to fit the outer diameter of the piston 60 ring casting. Passing through the interior of the casting and supported on the centers 35 of the lathe, is the bar 14 which is driven by the dog 15 engaged with the face plate 36 of the lathe. The bar 14 carries the hardened roller 16 mounted on the pin 17 which

passes through the adjustable support 18. This support has a threaded shank 19 which passes through the bushing 20 and carries the two nuts 21 at its end. The bushing 20 is threaded upon the outside and has a hexagonal section at its outer end so that it may be turned with a wrench and screwed in or out of the bar to adjust the position of the roller 16, being retained in its adjusted position by the lock nut 22. The rotation 70 of the support 18 in the bar is prevented by the pin 23 which also serves to prevent the endwise movement of the pin 17.

The method of operation used in connection with the apparatus just described is as 80 follows:

The piston ring casting is clamped securely in the holder 11 which, being a good fit on the outside of the casting, supports the metal at all points. The bar 14 is then 85 passed through the casting and supported on the centers while the cross slide of the tool carriage, supporting the work, is adjusted so that the axis of the casting is eccentric to the center line of the bar. Adjustment of the roller 16 is then made so that it bears upon the interior of the casting lightly at one point and, owing to its eccentricity, with a much greater pressure at the point diametrically opposite. By means 95 of the cross feed of the tool carriage and the adjustment of the roller, any desired degree of eccentricity or pressure of the roller upon the casting may be obtained.

Adjustments having been made, the bar is 100 revolved and the tool carriage fed longitudinally of the lathe so that the roller travels around the inside of the casting and, at the same time, advances from one end of it to the other, thus passing over the entire internal 105 surface of the casting and producing a compressing effect which is a maximum along a line parallel to the axis of the casting and decreases either way around the circumference from this line.

The arrangement shown in Fig. 9 is operated in the same way as that of Fig. 1, the only difference being in the method used for supporting and driving the bar which, in this case, is made to fit the taper hole in the 115 lathe spindle and is retained in position by the bolt 24.

In Fig. 13 the piston ring casting is supported in the holder 25 and carried on the face plate 26 of the lathe. The bar 27 has 120 one end rigidly clamped to the tool carriage and the other end supported by the bushing 28 which fits the tapered hole in the lathe spindle 29. With this arrangement, the eccentricity required between the path 125 of the roller and the interior of the piston ring casting is obtained by adjusting the position of the work holder upon the face plate, the amount of pressure developed being determined by the adjustment of the 130

roller as described above in connection with the arrangements already illustrated.

Apparatus for performing the rolling operation upon a drill press is shown in Fig. 5 17 where the bar 30 is driven by the spindle 31 and has its lower end guided in the bushing 32 carried in the table. The work holder 33 is adjustable upon the table to give the desired eccentricity and the position of the 10 roller relative to the axis of the bar is also adjustable as described above.

It will be understood that the method of this invention may be carried out by other means than those herein described, and in 15 this connection it will be noted that there is a relative travel of the means exerting pressure upon the interior of the piston ring casting both about the axis of the casting and lengthwise of the casting; that in its 20 lengthwise travel this means moves along lines of equal pressure, and that as it travels about the axis of the casting the pressure is varied by eccentric increments or decrements having a common axis of eccentricity. In 25 other words, the pressure at different points about the axis of the ring varies by amounts corresponding to the differences, at different points in the path of travel of the pressure exerting means about said axis, of the distances 30 between the inner surfaces of two rings of unequal diameters which are eccentric to each other and one of which completely surrounds the other. As the method is practised, the pressure exerted upon the 35 inner surface of the ring along any line parallel to the axis of the ring will be the same at all points along this line.

What we claim as new is:

1. The method of making piston rings 40 which comprises subjecting the internal cylindrical surface of the ring to rolling pressure, varying said pressure between a maximum upon one side of the axis of the ring and a minimum upon the opposite side, and 45 progressively advancing the application of said pressure along the axis of said ring.

2. The method of making piston rings 50 which comprises subjecting the internal cylindrical surface of the ring to rolling pressure traveling helically about the axis of said ring and varying said pressure between a maximum upon one side of said axis and a minimum upon the opposite side.

3. The method of making piston rings 55 which comprises closely confining the outer cylindrical surface of the ring and then subjecting the inner cylindrical surface to rolling wall compressing pressure, varying said pressure, as it travels about the axis of said 60 ring, by eccentric increments or decrements having a common axis of eccentricity, and advancing the application of said pressure along said axis in lines of equal pressure.

4. The method of making piston rings 65 which comprises closely confining the outer

cylindrical surface of the ring and then subjecting the inner cylindrical surface to rolling wall compressing pressure, varying said pressure, as it travels about the axis of said ring, by eccentric increments or decrements 70 having a common axis of eccentricity, advancing the application of said pressure along said axis in lines of equal pressure, and then cutting through said ring at the point where the pressure application has 75 been substantially least.

5. The method of making piston rings 80 which comprises subjecting the inner cylindrical surface of a hollow cylindrical casting of substantially uniform wall section to rolling wall compressing pressure, varying said pressure, as it travels about the axis of said cylinder, by eccentric increments or decrements 85 having a common axis of eccentricity, advancing the application of said pressure progressively along said axis in lines of equal pressure, cutting said cylinder into rings and then cutting through each ring at the point where the pressure application 90 has been substantially least.

6. The method of making piston rings 95 which comprises subjecting a hollow cylindrical casting of substantially uniform wall section to rolling wall compressing pressure varying from point to point around the circumference, and then cutting through said casting where the resultant internal tension is least.

7. The method of making piston rings 100 which comprises pressing the inner wall of a hollow cylindrical casting of substantially uniform wall section into the contour of a cylinder having its axis parallel but eccentric to that of the outer wall while positively maintaining the external shape and 105 size of said cylinder.

8. The process of making piston rings 110 which comprises confining exteriorly a hollow cylindrical casting of substantially uniform wall section, progressively exerting pressure upon the inner surface of said casting sufficient to form said surface into the contour of a cylinder having its axis parallel but eccentric to that of the outer surface and 115 then cutting through said wall at its thickest part.

9. The process of making piston rings 120 which comprises continuously supporting one side of the wall of a hollow cylindrical casting of substantially uniform wall section and then progressively exerting heavy pressure of varying intensity upon the other side of said wall.

10. The process of making piston rings 125 which comprises subjecting the wall of a hollow cylindrical casting of substantially uniform wall section to heavy pressure exerted progressively about the axis of the cylinder and varying gradually from a maximum upon one side of the cylinder to a 130

minimum at a point diametrically opposite and then back to said maximum, and then cutting through said wall at the point where the minimum pressure has been exerted.

5 11. The process of making piston rings, which comprises subjecting the wall of a hollow cylindrical casting, of substantially uniform wall section, to heavy pressure exerted progressively both about and along the 10 axis of the cylinder, and gradually varying said pressure from a maximum at points in a line parallel to said axis to a minimum at points in a line diametrically opposite to said first mentioned line, and then back to 15 said maximum.

12. The improvement in the art of making piston rings, which consists in positively confining a hollow cylindrical casting of substantially uniform wall thickness, 20 and then effecting a redistribution of the metal in said casting by pressure exerted progressively and variably along lines predetermined in such manner as to tend to form a structure having outer and inner 25 cylindrical surfaces with axes parallel but eccentric to each other.

13. The improvement in the art of making piston rings, which consists in effecting a redistribution of the metal in a hollow cylindrical casting, of substantially uniform wall section, by exerting rolling wall com-

pressing pressure progressively variably about the axis of said cylinder and along lines predetermined to produce a structure having its most compressed portion upon one 35 side and its least compressed portion diametrically opposite to the thinnest position, cutting said casting into rings and cutting through each ring where the wall compression is least.

14. The method of making piston rings which comprises confining exteriorly a hollow cylindrical casting of substantially uniform wall section and then compressing said 45 wall by rolling pressure applied upon the inner surface of said casting before forming the usual piston ring split.

15. The process of making piston rings, which comprises subjecting the wall of a hollow cylindrical casting, of substantially 50 uniform wall section, to heavy wall compacting pressure exerted progressively both about and along the axis of the cylinder before forming the usual piston ring split.

Signed at Detroit, Michigan, this 3rd day 55 of May, 1917.

JOHN F. DODGE.
WILLIAM J. ALLES.

It is hereby certified that in Letters Patent No. 1,255,142, granted February 5, 1918, upon the application of John F. Dodge and William J. Alles, of Detroit, Michigan, for an improvement in "Methods of Manufacturing Piston-Rings," an error appears in the printed specification requiring correction as follows: Page 4, line 37, claim 13, for the word "position" read *portion*; and that the said Letters Patent should be read with this correction therein that the same may conform to the record of the case in the Patent Office.

Signed and sealed this 19th day of March, A. D., 1918.

[SEAL.]

R. F. WHITEHEAD,

Acting Commissioner of Patents.
